UNITED STATES PATENT OFFICE.

FRANK L. SHOPPE, OF PASSAIC, EDWARD G. HEDGES, OF NEWARK, AND WALTER W. HEROU, OF BLOOMFIELD, NEW JERSEY.

FLUSH VALVE.

Application filed October 3, 1921. Serial No. 504,827.

To all whom it may concern:

Be it known that we, FRANK L. SHOPPE, residing at Passaic, county of Passaic, and State of New Jersey, EDWARD G. HEDGES, residing at Newark, county of Essex, and State of New Jersey, and WALTER W. HEROU, residing at Bloomfield, county of Essex, and State of New Jersey, all citizens of the United States, have invented certain new and useful Improvements in Flush Valves, fully described and represented in the following specification and the accompanying drawings, forming a part of the same.

The present invention relates to a flush-valve of the class that is shown and described in Patent No. 1,237,109 issued August 14, 1917, to Frank L. Shoppe for improvement in flush-tank valves, and the present invention embodies improvements in the construction of a flush-tank valve in which a column of water is held in an inverted water-chamber over the outlet-seat of the tank during the discharge or emptying of the tank.

Such column of water is utilized to sustain a float-valve above the seat until the tank is nearly empty, when the atmosphere gains access to the interior of the chamber through a water-inlet at its lower end, thus releasing the water-column and permitting the valve to drop quickly and close the outlet.

Such an inverted water-chamber is sometimes termed a "dome," and such title will, for convenience, be used herein, although the chamber is of cylindrical shape excepting the top, which is shown of dome-shape.

The invention embraces various desirable constructive features, including a means of securing an elastic valve-seat upon the outlet without any clamping-screws, means for securing the dome by a clamp operating upon the top of the dome to hold it detachably upon the valve-hub; also in the provision of lugs upon the float-valve to guide its movement within the water-chamber, and in means for securing an air-valve-plug upon the top of the float-valve, by enclosing the foot or anchor of the valve-plug in the substance of the float-valve, which is commonly made of glass.

These improvements will be understood by reference to the annexed drawing, in which Fig. 1 is an elevation of a flush-tank with the nearer side removed; Fig. 2 is a central vertical section of the water-chamber

or dome; Fig. 3 is a vertical central section of the outlet with the valve-seat and valve thereon; Fig. 4 is an edge view of the elastic seat; and Fig. 5 is a plan of the outlet and hub thereon.

The several figures are drawn upon different scales to exhibit the structure more clearly.

A designates the flush-tank in Fig. 1, and B the outlet fixture of the tank which is closed by the float-valve C. G is the dome encircling the valve and its seat a.

B' is a supply-pipe extended into the body of the tank and provided upon the top with a supply-valve E controlled by the valve-lever F. B' is the usual overflow pipe.

In the present construction, the body a' of the outlet requires no screws or lugs for attaching the dome thereto, but is formed with a short hub d encircling the valve-seat and formed upon the outer side with an annular rebate or shoulder d' to which the bottom of the dome G is fitted removably. The valve-seat rests on the body a' of the valve. See Fig. 3.

The interior of the hub is formed with an annular recess e or undercut channel to receive a collar b' on the elastic valve-seat a, shown in Figs. 3 and 4.

Owing to the elasticity of the rubber valve-seat it may be made a little larger than the recess, so that when crowded therein it firmly retains its position. The recess and the collar b' are shown of rectangular cross-section, but the upper or contiguous corners of both require, in practice, to be rounded so that the rib may slip into the recess without those corners interfering with one another. This is shown at e' in Fig. 3.

A clamping arm H is shown held movably upon the overflow pipe B' by a thumb-screw I, and the arm projects over the top of the dome G; so that when the arm is resting thereon and secured to the overflow pipe, the dome is held in the rebate d' upon the hub. The dome can be immediately removed from the outlet by loosening the screw of the clamping-arm and raising it from the dome.

An air-passage f is shown in the top of the dome formed with a valve-seat upon its inner side, and a guide-socket f' extending downwardly from the valve-seat, into which socket an air-valve h upon the float-valve

enters readily when the float-valve is raised for emptying the tank.

The float-valve, as shown in Fig. 2, is hollow and may be blown or molded of glass so as to float, and have the foot of the air-valve *h* anchored therein, as shown in Fig. 2, which may be effected during the molding operation.

The float-valve is proportioned to form a 10 clearance space for the passage of water between the sides of the valve and the chamber, and integral lugs *C* are formed upon the float-valve to nearly touch the dome, and thus guide the float-valve in its movements therein.

The float-valve is tapered downwardly to enter freely into the valve-seat *a* which is attached to the outlet, which seat has a thin flange flared upwardly to fit snugly to the 20 lower end of the float-valve.

Until the tank is nearly emptied and air gains access to the water-inlets *c*, the buoyancy of the float holds the air-valve pressed against the air-passage and prevents the 25 valve from descending, which would choke the outlet *B* and obstruct the free escape of water therefrom.

When the tank is filled in readiness for a flushing movement, the float-valve rests 30 upon the valve-seat *a* and the flushing movement is initiated by lifting the valve through the agency of the rod *g* which passes loosely through the air-passage *f* and is secured detachably in the air-valve *h*, 35 as by a screw-thread. The rod leaves space in the passage *f* for the air to move inward and outward.

When the escaping water is lowered to the 40 level of the inlets *c*, air enters the inlets, and the water-column immediately loses its support and flows directly to the outlet *B*, causing the valve *C* to descend upon the valve-seat *a*. This terminates the discharge 45 of the tank, and permits it to be immediately refilled by the supply-pipe *B'*.

The elastic seat heretofore used upon such valves has been secured upon the outlet by a metallic ring fitted over a flange upon the edge of the seat and connected to the outlet 50 by lugs and screws.

Such ring has usually been riveted to the bottom end of the dome, and access to the dome could be obtained only by removing the screws from the lugs.

55 As already pointed out, the dome in the present invention is held in place by the application of the clamping-arm *H* to its top, its lower end being fitted detachably to either the inside or outside of the hub *d* 60 to center it upon the outlet.

Having thus set forth the nature of the invention what is claimed herein is:

1. The combination, with a tank-outlet fixture having an outlet of a hub surrounding the seat and provided with an undercut 65 channel next the said seat, an elastic valve-seat crowded into said channel and an inverted water-chamber sustained upon the hub and provided with a water-inlet near the outlet-seat, and means operating upon the top of the chamber for holding it detachably upon the hub.

2. The combination, with a tank-outlet fixture having an outlet of a hub surrounding the seat and provided with a recess or 75 undercut channel within the hub next the seat, an elastic valve-seat crowded into said channel, a dome sustained upon the hub and provided with a water-inlet near the outlet-seat, a float-valve fitted to said seat and 80 movable upward within the chamber, an overflow tube extended upward from one side of the hub in connection with the tank-outlet, and a clamping-arm secured movably upon the overflow tube to engage the top of 85 the dome and hold it removably upon the hub.

3. The combination, with a tank-outlet fixture having an outlet of an inverted water-chamber fitted detachably around the 90 water-outlet with water-inlets near the seat, an elastic valve seat fitted within the hub, a float-valve fitted to the said seat and movable upward within the chamber and having clearance space between the sides of the 95 valve and the chamber, and guide-lugs upon the valve to center it in the chamber.

4. The combination, with a tank-outlet having a valve-seat with an undercut channel and an elastic valve-seat crowded therein, of an inverted water-chamber fitted detachably around the water-outlet, a float-valve movable to and from the valve-seat within the chamber, with clearance space between the sides of the valve and the chamber, and integral guide-lugs upon the valve to center it in the chamber, an air-passage through the top of the chamber with valve-seat therein, an air-valve upon the top of the float-valve, and a lifter-rod smaller than 100 the air-passage extended through the same and detachably engaged with the valve-plug, and means operating upon the top of the chamber for holding it detachably upon the outlet.

110 In testimony whereof we have hereunto set our hands.

FRANK L. SHOPPE.
